UNITED STATES PATENT OFFICE.

LESTER L. GLIDDEN, OF NATICK, MASSACHUSETTS, ASSIGNOR TO UNITED SHOE MACHINERY COMPANY, OF PATERSON, NEW JERSEY, A CORPORATION OF NEW JERSEY.

HEELING-MACHINE.

1,157,688.

Specification of Letters Patent.

Patented Oct. 26, 1915.

Application filed November 2, 1910. Serial No. 590,271.

To all whom it may concern:

Be it known that I, LESTER L. GLIDDEN, a citizen of the United States, residing at Natick, in the county of Middlesex and 5 State of Massachusetts, have invented certain Improvements in Heeling-Machines, of which the following description, in connection with the accompanying drawings, is a specification, like reference characters on 10 the drawings indicating like parts of the several figures.

This invention relates to machines for operating upon the heels of boots or shoes. In 15 the following specification and accompanying drawings the invention is described and illustrated as embodied in a machine for attaching heels to shoes, but it should be understood that this is for the purpose of illustration, and should not be construed 20 as a limitation of the scope of the invention.

In performing operations upon the heels of shoes, such, for example, as heel attaching, top lift spanking, etc., the work is usually supported upon a jack or equivalent 25 device. It is a common practice to support a shoe upon a last mounted upon a jack and to effect relative movement between the jack and a corresponding pressing member, such as a nailing die, to compress and hold the 30 work while a tool operates upon it, it may be to drive heel attaching nails therethrough. The thickness and density of the stock used in shoe soles vary considerably, and the density and height of heels are sub- 35 ject to very wide variation. The height of wood lasts, upon which welt shoes are usually heeled, is also a very uncertain factor, which must be taken into consideration in positioning the work pressing and hold- 40 ing members and it has always been a serious problem with inventors and designers of heeling machinery for use with wood lasts to provide mechanism for compensating for the varying thickness of the work and last 45 in such a way as to insure the application of a uniform and sufficient pressure to the work while avoiding danger of breaking or crushing the last by excessive pressure.

The aim of the present invention is to 50 provide a machine which will operate rapidly and turn out high grade, uniform work under the differing conditions above mentioned, with a minimum of labor and skill upon the part of the operative. To this 55 end an important feature of the invention

resides in the provision in a machine having a shoe support and a coöperating pressing member, such as a nailing die, of means for automatically effecting relative approaching movement of the shoe support and die, 60 whereby those members are preliminarily positioned in contact with the work a distance apart dependent upon the thickness of the work and means for them effecting a further predetermined relative movement of 65 the members mentioned, for the purpose of giving the work a uniform amount of compression. Preferably the initial approaching movement, or measuring, is effected by spring operated mechanism, whereby a definite, substantially uniform measuring pressure is brought to bear upon the work irrespective of its thickness and without regard to the care or skill exercised by the operative; and a predetermined amount of additional approaching movement is then effected 70 by power mechanism to compress the work. In the specific machine hereinafter described I have shown the mechanism for effecting the last mentioned movement as embodied 75 in power operated means for moving the nailing die toward the jack, but it should be understood that it is within the invention to move either or both of said members.

While it is preferable that the above mentioned operations be effected automatically by the simplest possible mechanism, it is desirable that they be separately under the control of the operator so that he may inspect the work after it has been located and 80 measured and before it has been operated upon. A further feature of the invention accordingly consists in the provision of a single manually operated device for controlling, first the operation of the automatic 85 measuring mechanism, and then the operation of the power operated pressure applying mechanism. This device may comprise a treadle which, upon being depressed, releases the spring means for actuating the 90 measuring mechanism, after which further movement of the treadle starts the power mechanism of the machine.

As herein shown the connection between the treadle and the mechanism for effecting 105 the measuring operation is interrupted as soon as said mechanism has been set in motion. This feature of the invention is of importance because it insures that the measuring pressure shall be effected entirely au- 110

tomatically and consequently uniformly. It also prevents the operator from subjecting the work to an excessive measuring pressure as has sometimes happened in those machines where the measuring is effected manually.

In the preferred form of my invention means is provided for preventing the shoe support from yielding under the heavy pressure exerted upon the work by the nailing die. I have illustrated this means as consisting of a plurality of interdigitally arranged wedges placed in the connection which transmits measuring movement from the spring or springs to the shoe support. The wedges, in addition to transmitting movement to the shoe support, act as locking means, preventing the shoe support from yielding under pressure.

A further feature of the invention resides in the provision of positive connections between the mechanism which supplies the power for compressing the work and the work engaging member moved by it, said positive connections being capable of such adjustment that a variation in the amount of movement of the work engaging member may be secured while the movement of the power actuating mechanism is always the same. In a satisfactory construction for effecting this result the connections above referred to include a toggle and a connecting link for straightening and breaking the toggle, the connecting link being adjustable in length so that the amount by which the toggle is broken may be varied and consequently the amount of movement effected by it may be controlled.

Further features of the invention have relation to the improvement of the controlling means for the movements of the heel and top lift holder and various details of mechanism for actuating the work support and nailing die.

The preferred embodiment of the invention is illustrated in the accompanying drawings, in which,

Figure 1 is a side-elevation of a complete machine. Fig. 2 is a front-elevation of the lower parts of the machine, with parts broken away to illustrate details of construction. Fig. 3 is a vertical section on the line 3—3, in Fig. 2. Fig. 4 is a section similar to Fig. 3 showing the parts in another operative position. Fig. 5 is a section on the line 5—5, in Fig. 1. Fig. 6 is a detail view, showing in rear-elevation a portion of the jack-adjusting mechanism and of the mechanism for controlling the movements of the heel and top-lift carrier, with the heel holder locked in operative position; and Fig. 7 is a horizontal section on the line 7—7, of Fig. 6.

In the illustrated embodiment of the invention the shoe 11 (Fig. 1), to which the heel is to be applied, contains a wood or iron

last which is secured to the lower end of the swinging jack 12. The jack is pivoted at its upper end to an adjustable jack-carrier 13 carried at the lower end of a vertically-sliding plunger 14. By means of an adjusting screw 16, turned by a hand-wheel 17, the plunger is connected with a universal joint 18 at the forward end of the walking-beam 19, which is pivoted at 21 on the frame of the machine in the usual manner. To the other end of the walking-beam is pivoted the upper end of a rod 22 by which the position of the walking-beam, and thus the vertical position of the jack, is controlled.

The means for actuating the rod 22 constitute a novel feature of the present invention. The lower end of this rod is fixed in a block 23 which slides vertically in a bracket 24 fixed to the frame of the machine. On the lower surface of this block is a dove-tailed guide-way engaging a correspondingly-formed projection on a wedge 25. The wedge 25 is the uppermost of a series of four oppositely-disposed wedges, designated as 25, 26, 27, and 28 respectively, each of these wedges being slidably connected with those above and below by means of tongue-and-groove projections and recesses as shown particularly in Figs. 3 and 4; and the lowermost wedge 28 has also a tongue-and-groove sliding connection with a guide 29 fixed upon the bracket 24. As shown in Fig. 6, the arrangement of the wedges is such that if the wedges 25 and 27 be moved to the left, and the wedges 26 and 28 be moved simultaneously to the right, the block 23 and the rod 22 will be raised, while, upon an opposite movement of the wedges, the block and the rod will be drawn downward positively, owing to the tongue-and-groove connections between the wedges. To actuate the wedges as just described, each wedge has a rack formed upon its rear surface, and these racks are so arranged that those on the wedges 25 and 27 are engaged by a vertical pinion 31, while those on the other two wedges are engaged by a vertical pinion 32. These pinions are loosely journaled upon studs mounted in the bracket 24. The pinions are actuated by means of a rack 33, which is located between their lower portions and has teeth engaging both pinions, as shown in Fig. 7, so that when the rack is moved longitudinally the pinions are rotated simultaneously in opposite directions.

The rack 33 is actuated in one direction by springs 34, of which the rear ends are attached to a pivot-pin 35 mounted in the lugs on the rack. The forward ends of these springs have adjustable connections 36 with the frame of the machine. When the mechanism just described is free to operate, the springs draw the rack forward, thereby rotating the pinions and moving the wedges in such a direction as to raise the block 23 and

the rod 22. Through this operation the walking-beam 19 is swung about its pivot, thereby lowering the stem 14 of the jack, and this movement continues until the heel-seat of the lasted shoe has been brought into close engagement with a heel held in the heel-holder, or, in the case of the operation of affixing the top-lift, until the heel, which has previously been nailed to the shoe, has been brought close to the top-lift. The mechanism thus automatically compensates for the varying height or thickness of the work, whatever it may be, and also applies a predetermined substantially uniform amount of pressure to the work before the other parts of the machine operate to compress and nail the heel or to spank the top-lift upon the heel, as the case may be. In this connection the adjusting-screw 16 is not essential and may be omitted, but it is preferred to retain this device as it permits a preliminary adjustment by which the position of the parts is roughly approximated to the class of work upon which the machine is to operate, thereby relieving the automatic mechanism of unnecessary movement. The object in employing a plurality of wedges in the mechanism just described is to permit the use, in each wedge, of a slight angle of inclination, while at the same time securing the necessary amplitude of movement. By this arrangement the wedge-mechanism is rendered self-locking, so that although it is thrown into operation, to lower the jack, by means of springs only, it positively resists the tendency of the jack to yield and rise when the compressing mechanism operates upon the work.

The wedge-mechanism is maintained in inoperative position, that is, in the position in which the jack is raised, by means of a rod 37 pivoted at its rear end upon the pin 35 on the rack 33. This rod slides between upwardly-extending guides 38 mounted upon the pitman 39 by which the nailing mechanism is actuated. Between the guides 38 is a detent-pin 41 which normally engages a shoulder 42 on the rod 37, thereby retaining the rod and the rack in rearward position in opposition to the tension of the springs 34, and thus retaining the wedge mechanism in a position of Fig. 6. After the operator has placed a lasted shoe upon the jack in position to receive a heel, it is necessary to release the wedge mechanism to permit the shoe to engage the heel, and this is accomplished by means of the treadle 43 employed, as is common in such machines, to control the operation of the nailing-mechanism.

This treadle is pivoted at 44 on the frame of the machine, and it has an upwardly-extending arm 45 which engages the lower end of an arm 46 depending from a rock-shaft 47 journaled on the pitman 39. A second arm 48 on the rock-shaft is adapted to engage the forward extremity 49 of the detent-rod 37, but the arm 48 is normally held in lowered position by a spring 51. With the parts in the position shown in dotted lines in Fig. 3, which is their normal position, if the treadle be slightly depressed, to the position shown in full lines in said figure, the mechanism just described operates to raise the detent-rod 37 as shown, thereby disengaging it from the detent-pin 41 and allowing the springs 34 to move the rack 33 forward.

The nailing mechanism is controlled by the treadle 43. To this end the treadle has an upwardly-extending rearward extremity 52. When the treadle is fully depressed, this extremity engages an arm 53 on a rock-shaft 54 journaled in the frame of the machine. A second arm 55, extending upward from the rock-shaft, coöperates at its upper extremity with a lug 56 on the driving clutch of the machine, which is of the well known Horton type. This clutch is employed to connect the driving shaft 58 of the machine intermittently with the fly wheel 57 by which the shaft is actuated, and to impart a single rotation to the shaft at each operation of the clutch, in the usual manner. The arm 55 is normally held in engagement with the lug 56, so as to hold the clutch out of operation, by means of a spring 55^a coiled about the rock-shaft 54.

The central portion of the drive-shaft is formed as a crank 59 upon which the pitman 39 is pivoted, and the forward end of the pitman is pivoted on a pin 62 constituting the middle joint of the toggle by which the nail-driver is actuated. This toggle comprises upper and lower arms 63 and 64 respectively. The lower arm is pivoted upon a block 65 adjustably fixed in the frame of the machine. The upper arm is pivoted to the lower end of a slide-block 66 which moves vertically in a guide 67 on the frame of the machine. This slide-block is not connected directly with the nail-drivers, but has provision for lost motion, whereby it operates the nail-drivers only during the last part of its upward movement. To this end the block 66 is guided upon a stem 68 which is fixed to, and projects downwardly from, the plunger 69 by which the driver-block 72 is directly actuated. This plunger moves vertically in the guide 67 and in an upper guide 71 also fixed on the frame of the machine.

The present machine is so arranged that the compressing movement of the nailing-die against the work is positive, and is independent of the movement of the nail-drivers. This general mode of operation is not novel in the present machine and is not broadly claimed herein as a part of the present invention, but the present machine embodies novel and simple mechanism for carrying out this mode of operation. The nailing-die 73 is removably mounted in a cross-head 74.

fixed to the upper end of two vertical rods 75 (Fig. 2). These rods are fixed, at their lower ends, in a second cross-head 76 which is free to slide upon the stem 69. The cross-head 76 is supported upon two toggles 79 which are pivoted at their lower ends on the frame of the machine. The central pivots 81 of the toggles 79 are connected with the forward ends of adjustable links 82, and the rear end of each link is pivoted at 83 to a cam-lever 84, (Fig. 3). Each cam-lever has, at its upper end, a cam shaped slot 85 engaging a pin 86 on the frame of the machine, while the lower end of each cam-lever is pivoted, at 87, on an arm 88. Each of the links 82 comprises in its construction a turn buckle 82^a and two oppositely threaded screws 82^b and 82^c. Each of these screws has an eye formed at one end and the pivots 81 and 83 pass through the eyes of the screws 82^b and 82^c, respectively. Upon each turn buckle is rigidly secured a sprocket wheel 82^d and an endless sprocket chain 82^e passes around the two sprocket wheels 82^d. Provision is thus made for controlling the amount of compressing movement of the nailing-die. By adjusting the turn buckles 82^a the amount by which the toggles 79 are broken may be varied and, consequently, the amount of upward movement of the nailing die may be controlled, since equal forward movements of a pivot 81 will produce different amounts of upward movement of the cross head 76 when said forward movements begin at different points. The connection of the turn buckles by the sprocket chain 82^e insures that both turn buckles will rotate together and both toggles will receive the same adjustment. Thus, although the path and amount of movement of the cam lever 84 and the pivot 83 are invariable, the amount of upward movement of the nailing die and, therefore, the amount of compression of the work may be varied between limits determined only by the size and proportions of the parts. The two arms 88 are connected by a bar 89, which is pivotally mounted concentric with the rock-shaft 54. From the bar 89 an arm 90 extends rearwardly and is pivoted to the lower end of a link 91. The upper end of this link is pivoted at 92 on the pitman 39.

In the normal inoperative position of the machine the pitman occupies the position shown in Fig. 3, and at this time the cam-levers 84 are in such position that the links 82 are drawn rearwardly and the toggles 79 are broken and the nailing-die lowered. As soon as the drive-shaft is operated in the direction of the arrow in Fig. 1, thereby raising the pitman during the first 90° of such rotation, the mechanism above described operates to draw the cam levers 84 downward, thereby causing the upper portions of their cam slots to engage the pins

86. Through this action the upper ends of the cam levers are thrown forward, thereby moving the toggles 79 toward their straight-line position as in Fig. 4, and thus raising the nailing-die through the predetermined distance necessary to compress the work to the required extent. During this operation the pitman is also moving forward so as to straighten the toggle by which the nail-drivers are actuated, but this movement is at first idle, owing to the lost motion in the connections above described. At this time the position of the nail-drivers is determined by sleeves 78 depending from a cross-head 77 in which the driver-block is mounted, this cross-head being fixed on the upper end of the stem 69. These sleeves, at their lower extremities, engage the cross-head 76, so that when the nailing-die rises to compress the work, as above described, the drivers are raised with it, and thus the drivers 72^a are maintained in engagement with the nail holes in the die. During the latter part of the forward movement of the pitman, after the compressing operation has been performed, and after the lost motion has been taken up in the toggle connections, the stem 69 is raised by the toggle, thereby driving the nails from the die into the work. The pressure toggles 79 are maintained in their straight-line position until the conclusion of the driving operation by reason of the fact that the arm 90 is held up by the link 91 during the forward motion of the pitman 39 and the rise imparted to the end 62 of the pitman as the driver toggle 63, 64 is straightened. The heel is thus held upon the shoe under heavy pressure until the attaching nails are driven and clenched. In the return movement of the pitman 39 the detent pin 41 again engages the shoulder 42 on the rod 37 and moves the rod and the rack 33 rearward in order to place the springs 34 under tension for the next operation.

In surface nailing it is necessary to drive the nails completely into the work, and therefore the ends of the drivers 72^a must be raised to the upper surface of the nailing-die. In blind nailing, on the other hand, it is necessary to leave portions of the nails projecting from the work, and in this case the drivers 72^a must not be raised so high in the nailing-die. To permit convenient adjustment of the drivers for these two modes of operation, the driver-block is adjustably mounted on the cross-head 77. To this end it is provided with horizontal lateral tongues 93 engaging corresponding grooves in a block 94. This block has inclined lateral tongues 95 engaging corresponding grooves in the cross-head 77. From the front of the adjusting-block 94 a lug 96 depends, and this lug is connected with the cross-head by means of an adjust-

ing-screw 97. By means of this screw the block may be moved forwardly or rearwardly on the cross-head, and such movement, acting through the inclined tongues 5 and slots, raises or lowers the adjusting block and with it the nail-drivers. During this adjusting movement the relative horizontal position of the nail-drivers and the nailing-die is preserved, owing to the tongue 10 and groove connection between the driver-block and the adjusting-block.

As shown in the drawings, the heel holder 98 and the top-lift holder 99 are carried by a plate 101 which moves horizontally on the 15 cross-head 74, being pivoted thereto by a pin 102. The nail-templet 103 by which nails are introduced into the die is carried on an arm 104 pivoted at 105 on the frame of the machine. By means of a handle 100 the 20 templet is swung into position above the die. By this same movement the heel and top-lift carrier is swung into position to bring the heel holder above the die, the arm 104 being provided with a pusher 106 which 25 engages a pin 107 on the plate 101 for this purpose.

The nails are supplied to the templet 103 by any ordinary or suitable automatic nail-feeding apparatus, and neither this apparatus nor any of the parts just described is 30 novel in the present invention. The means for locking the heel and top-lift carrier in the heel-nailing position, and for returning it to normal position, are, however, novel. 35 The plate 101 is connected with the forward end of a rod 108 of which the rear end is pivoted to an arm 109 at the upper end of a vertical rock-shaft 111. This rock-shaft is journaled in a bracket 112 fixed to the rear 40 of the frame of the machine, and a spring 113 coiled about the rock-shaft is connected at one end with the bracket and at the other end with the shaft. This spring tends constantly to rock the shaft and the arm 109 in 45 a direction to pull upon the rod 108 and thus to swing the heel and top-lift carrier to the position of Fig. 5, that is, with the top-lift holder above the nailing-die. After the heel and top-lift carrier has been moved, as above 50 described, to bring the heel above the nailing-die in position to be secured to the shoe, it is necessary to retain the carrier in this position against the action of the spring 113 until the heel has been nailed. To this end a 55 locking device is provided for the rock-shaft 111. An arm 114 extends inwardly from the upper end of the rock-shaft, and this arm has a vertical socket in which is slidingly mounted a latch 115 provided with a bevelled surface 116, as shown particularly in Fig. 5. This latch is normally pressed upward by a spring 117. When the parts are moved in opposition to the spring 113 the latch passes under a keeper 118 mounted in

65 an arm 119 extending upwardly from the

bracket 112. The latch passes freely under and to the rear (Fig. 6) of the keeper when moving in this direction, but its return is prevented, and thus the return movement of the rock-shaft is prevented, until the latch 70 is released at a suitable time in the operation of the machine.

To release the latch above described and permit the spring 113 to move the heel and top-lift carrier into position to present a 75 top-lift above the nailing-die, a bracket 121 is clamped upon the rod 22, and this bracket has a horizontal sleeve in which is slidingly mounted a trip 122. This trip is normally forced forward by a spring 123 and its forward beveled extremity cooperates with a beveled head 125 on the lower end of the latch 115. When the rod 22 moves upward, during the first part of the operation of the machine, the trip yields and idly passes 80 above the head 125, but, after the completion of the heel-nailing operation, when the rod 22 descends the trip pushes the head 125 downward, thereby withdrawing the latch from engagement with its keeper, and 85 thus releasing the heel and top-lift carrier, so that it returns to normal position, and this brings a top-lift into position to be attached to the heel upon the next rotation of 90 the drive-shaft.

In connection with the mechanism for throwing the driving-clutch into operation, a safety-device is provided to insure against accidental operation of the clutch. To this end the rock-shaft 54 has an upwardly-projecting arm 126 carrying at its upper end a pin 127 adapted to engage a shoulder 128 on a horizontal lock-bar 129. The forward end of this bar is pivoted to the toggle-pin 62, and the rear end is pivoted to a rod 132 of which the lower end is pivoted to the rear end of the treadle 43. When the treadle is operated, the rod 132 raises the lock-bar 129, so as to disengage the shoulder 128 from the pin, but after the treadle is released, if the spring 55^a fails to return the clutch arm 55 to operative position, the movement of the toggle-pin 62 causes the lock-bar 129 to swing the arm 126 rearwardly, thereby turning the rock-shaft 54 and throwing the 115 arm 55 positively into engagement with the clutch-lug 56.

Since the automatic adjustment of the jack compensates, at each operation of the machine, for the varying thickness of the work, it is immaterial whether a heel, or both a heel and a top-lift, be between the jack and the die, at any particular operation of the machine, and for this reason either the nailing operation or the top-lift-applying operation may be repeated whenever necessary, without any manual adjustment of the machine on the part of the operator.

The use of the same treadle to control both the jack adjustment and the nailing and 130

compressing operations simplifies the control of the machine, since it enables the operator to have both hands free at all times to handle the work and the nail templet.

5. My invention is not limited to the embodiment thereof hereinbefore described and illustrated in the accompanying drawings, but may be embodied in various forms within the nature of the invention as it is defined in the following claims.

10. What is claimed as new is:—

1. A heel-attaching machine having, in combination, a nailing-die, a jack, automatic means for moving the jack toward the die, while the die is stationary, through a distance determined by the thickness of the work, and means operating, after said movement of the jack, to move the die toward the jack to compress the work, and thereafter to drive nails into the work.

2. A heel-attaching machine having, in combination, a nailing-die, a jack, automatic means for moving the jack toward the die, while the die is stationary, through a distance determined by the thickness of the work, and means operating, after said movement of the jack, to move the die toward the jack, through a predetermined distance, to compress the work, and thereafter to drive 20 nails into the work.

3. A heel-attaching machine having, in combination, a nailing-die, a jack, automatic means for moving the jack toward the die until arrested by the engagement of the work, and means operating, after said movement of the jack, to move the die toward the jack to compress the work, and thereafter to drive nails into the work.

4. A heel-attaching machine having, in combination, coöperating members comprising a nailing-die and a jack, and automatic means for adjusting the distance between said members comprising a yielding device for moving one member toward the other, locking mechanism for holding the member so moved in adjusted position, and positive means for moving said member in the opposite direction.

5. A heel-attaching machine having, in combination, coöperating members comprising a nailing-die and a jack, and automatic means for adjusting the distance between said members in conformity with the thickness of the work comprising locking mechanism including a series of oppositely-disposed wedges, and means for moving the contiguous wedges simultaneously in opposite directions.

6. A heel-attaching machine having, in combination, a nail-driver, a nailing-die, means for actuating the nail-driver comprising a toggle, a pitman connected with the toggle, and a crank connected with the pitman, and means for actuating the nailing-die comprising a toggle, a cam-lever con-

7. In a machine for operating upon heels, the combination of coöperating pressing members arranged for relative approaching movement, automatic means for moving one of said members toward the other while the latter is stationary until a predetermined definite pressure is exerted upon the work, and power means for moving one of said members toward the other to effect complete compression of the work.

8. A heel-attaching machine having, in combination, nailing devices, a jack, jack-adjusting mechanism for moving the jack toward and from the nailing-devices, a heel and top-lift carrier, and means for moving said carrier into position to present a top-lift to the shoe, said means being connected with, and controlled by, the jack-adjusting mechanism so as to operate when the jack is moved away from the nailing devices.

9. In a heel attaching machine the combination of coöperating members including a jack and a nailing die, power mechanism for moving one of said members toward the other to bring parts of the work together, mechanism for moving the latter member toward the former to subject the work to pressure, and a single controlling device connected with said mechanisms and arranged to throw one mechanism into operation upon a partial movement of said device, and the other mechanism into operation upon a further movement of said device.

10. A heel-attaching machine having, in combination, coöperating members including a jack and a nailing-die, power mechanism for moving one of said members toward the other to bring parts of the work together, mechanism for moving one of said members toward the other to subject the work to pressure, and a single controlling device connected with said mechanisms and arranged to throw one mechanism into operation upon a partial movement of said device, and the other mechanism into operation upon a further movement of said device.

11. In a heel attaching machine, the combination of a movable nailing die, actuating mechanism for moving said die in two directions, said mechanism having an invariable amount of movement, and positive power transmitting connections between said mechanism and said die constructed to permit variation of the amount of movement of the die.

12. In a heel attaching machine, the combination of a work support, a nailing die, actuating mechanism for moving one of said members relatively to the other to compress and release the work, and unyielding power

5 of said members to bring members into engagement with the work, and means for transmitting connections between said actuating mechanism and said moving member constructed to permit variation of the amount of movement of said member without a corresponding variation of the amount of movement of the actuating mechanism.

13. In a heel attaching machine the combination of a work support, a nailing die, actuating mechanism for moving one of said members relatively to the other to compress the work, normally inextensible power transmitting connections between said actuating mechanism and said moving member, and means for varying the amount of movement of said member without affecting said actuating mechanism.

14. In a heel attaching machine the combination of a work support, a nailing die, actuating mechanism for moving one of said members relatively to the other to compress the work, normally inextensible power transmitting connections between said actuating mechanism and said moving member, and means for varying the amount of movement of said member without effecting a corresponding variation of the amount of movement of the actuating mechanism.

15. In a machine for operating upon heels, the combination of cooperating pressing members arranged for relative approaching movement, means for automatically moving one of said members toward the other through a variable distance until it exerts a predetermined definite pressure upon the work, and automatic means for moving one of said members toward the other to compress the work.

16. In a machine for operating upon the bottoms of boots or shoes, the combination of a work supporting member and a cooperating pressing member, constructed and arranged for relative approaching movement, automatic means for actuating one of said members to exert a predetermined pressure upon the work to measure the thickness thereof and additional automatic means for actuating one of said members to compress the work.

17. In a machine for operating upon heels, the combination of a work supporting member and a cooperating pressing member, arranged for relative approaching movement, automatic means for applying a predetermined force to one of said members, said force being transmitted by said member to the work, and automatic means for moving the other of said members to compress the work.

18. In a machine of the class described, the combination of a work supporting member and a presser member arranged for relative approaching movement, spring operated means acting unassisted to move one of said members into engagement with the work to measure the work, and means for moving the

other of said members toward the first to compress the work.

19. In a machine of the class described, the combination of a work supporting member and a presser member arranged for relative approaching movement, spring operated means acting unassisted to move one of said members into engagement with the work to measure the work, and means for positively moving the other of said members toward the first to compress the work.

20. In a heelng machine, the combination of a jack, a nailing die, spring operated means acting unassisted to move the jack toward the die to measure the work, and positive means to move the die toward the jack, to compress the work.

21. In a heelng machine, the combination of a jack, a nailing die, automatic means for moving one of said members toward the other through a variable distance to measure the work, and automatic means for moving the other member toward the first, to compress the work, and thereafter to drive nails into the work.

22. In a heelng machine, the combination of a jack, a nailing die, automatic means for moving one of said members toward the other with a predetermined, definite force, to measure the work, automatic means for moving the other member toward the first, to compress the work, and automatic means for positively moving the die away from the jack.

23. In a machine for operating upon heels, the combination of a work supporting member and a pressing member arranged for relative approaching movement, spring operated means acting unassisted to effect relative approaching movement of said members to measure the work, additional means for effecting further approaching movement of said members to compress the work, and means for presenting a heel or a top lift in position to be pressed upon a shoe upon the work supporting member by the relative approaching movement of said members.

24. In a machine for operating upon heels, the combination of a work supporting member and a pressing member arranged for relative approaching movement, spring operated means acting unassisted to effect relative approaching movement of said members to measure the work, additional means for positively effecting further approaching movement of said members to compress the work, and means for presenting successively a heel and a top lift in position to be pressed upon the shoe by successive relative approaching movements of said members.

25. In a heel nailing machine, power operated nailing mechanism, cooperating work pressing members relatively movable to measure the work, spring operated means for preliminarily and automatically moving

one of said members, and a starting lever arranged to release said means during its initial movement and then to move farther without affecting said movable member, said lever in its further movement throwing the nailing mechanism into operation.

26. In a heel nailing machine, nailing mechanism, a power operated actuator therefor, coöperating work pressing members, a 10 spring operated actuator for moving one of said members to measure the work, and a starting lever having independent connections with the power operated actuator and the spring operated actuator, said connections being effective successively, and the connection with the spring operated means being interrupted after an initial movement of the starting lever.

27. In a heel nailing machine, nailing 20 mechanism, a power operated actuator therefor, coöperating work pressing members, a spring operated actuator for moving one of said members to measure the work, and a starting lever having independent connections with the power operated actuator and the spring operated actuator, said connections being effective successively.

28. In a heel attaching machine, the combination of nail driving mechanism, co- 30 operating work engaging members, comprising a nailing die and a shoe support, one of said members being automatically movable toward the other while the latter is stationary, to measure the work, and power means 35 for positively moving one of said members toward the other to compress the work, and for thereafter driving nails into the work.

29. In a heel attaching machine, the combination of nail driving mechanism, co- 40 operating work engaging members, comprising a nailing die and a shoe support, one of said members being automatically movable toward the other while the latter is stationary, to measure the work, power means for 45 positively moving one of said members toward the other to compress the work and for thereafter driving nails into the work and mechanism for starting the power means, arranged to be operated after the work has 50 been measured.

30. In a heel attaching machine, coöperating work engaging members, comprising a shoe support and a nailing die, a source of power, automatic means for moving one of 55 said members toward the other to compress the work, one of said members being initially movable toward the other automatically to measure the work with a predetermined, definite pressure independently of said 60 means, and devices for connecting said means to the source of power.

31. In a heeling machine the combination 65 of drivers, coöperating work pressing members including a nailing die, power actuated means for positively moving the nailing die

to subject the work to pressure and for thereafter reciprocating the drivers, one of said pressing members being preliminarily movable automatically toward the other independently of the power actuated means for 70 the purpose of subjecting the work to a predetermined measuring pressure, and a treadle arranged to be operated to start the power actuated means after the work has been measured. 75

32. In a heeling machine the combination of work pressing members comprising a shoe support, and a nailing die supported in a holder guided for vertical movement, one of said members being automatically movable 80 toward the other under the influence of a definite force to measure the work, and power actuated means for moving said holder and die vertically toward the shoe support to compress the work and for there- 85 after driving nails into the work.

33. In a machine for operating upon heels, the combination of coöperating pressing members, including a shoe support and a nailing die, automatic means for effecting 90 approaching movement of said members to measure the work, mechanism for effecting further approaching movement of said members to compress and hold the work, a power operated tool, and means for storing power 95 in said automatic means during one cycle of operation of the machine to be used during the next cycle.

34. In a heel nailing machine, the combination of a shoe support, a nailing die, power operated nail drivers, spring operated means acting unassisted to move the shoe support toward the die to measure the work, positive means for moving the die toward the shoe support to compress and hold the work, and means for storing power in the spring during one cycle of operation of the machine to be used during the next cycle. 100

35. A heel attaching machine having, in combination, a jack and a nailing die arranged for relative approaching movement to engage the work, a gang of nail drivers, a spring connected to one of the work engaging members and arranged to effect completely their relative approaching movement 110 to engage the work and measure its thickness, power operated mechanism for energizing the spring, and manual means for controlling its operation. 115

36. In a heel attaching machine, the combination of a relatively movable jack and nailing die, a power driven gang of nail drivers for driving attaching nails into the heel, mechanism for effecting relative approaching movement of the jack and nailing die arranged to be completely energized by the power of the machine during the movement of the nail drivers in one direction, and manually controlled means for causing the said mechanism to effect said relative 120 125 130 movement.

movement to clamp the work with a uniform pressure.

37. In a heel attaching machine, the combination of a shoe supporting member and a coöperating pressing member arranged for relative approaching movement, automatic means for moving one of said members toward the other while the latter is stationary until a predetermined, definite 10 measuring pressure is exerted upon the work, power means for moving one of said members farther toward the other to apply additional pressure to the work, and means for presenting a heel in position to be 15 pressed upon the shoe by the relative approaching movement of said members.

38. In a heel attaching machine, the combination of a shoe supporting member and a coöperating pressing member arranged 20 for relative approaching movement, means for automatically moving one of said members toward the other until it exerts substantially uniform pressure upon the work irrespective of its thickness, automatic 25 means for moving one of said members toward the other to compress the work, and means for presenting successively a heel and a top lift in position to be pressed upon the shoe by successive relative approaching 30 movements of said members.

39. In a machine for operating upon the bottoms of boots and shoes, the combination of a work supporting member and a coöperating pressing member, constructed and 35 arranged for relative approaching movement, automatic means for actuating one of said members to exert a measured pressure upon the work to measure the thickness thereof, and additional automatic means, 40 positively and permanently connected to one of said members, for actuating it to compress the work.

40. In a heel attaching machine, the combination of a shoe supporting member and 45 a coöperating pressing member, constructed and arranged for relative approaching

movement, means for presenting a blank between said members, automatic mechanism for effecting relative approaching movement of said members, constructed and 50 arranged to apply and maintain a substantially uniform pressure upon the work irrespective of its thickness, and automatic means for then effecting compression of the work. 55

41. In a heel attaching machine, the combination of mechanism for driving simultaneously a gang of heel attaching nails, coöperating pressing members arranged for relative approaching movement, automatic 60 means for moving one of said members toward the other, to compensate for the varying thickness of the work and to apply and maintain a substantially uniform pressure upon the work irrespective of its thickness, 65 and automatic means for moving one of said members toward the other to effect compression of the work prior to the completion of the nail driving operation.

42. A machine for operating upon heels, 70 having, in combination, oppositely arranged pressing members, tools for operating on a heel held by said members, a device constructed and arranged to be moved by the power of the machine during each cycle and 75 to be latched under spring tension when the machine comes to rest, a train of mechanism actuated when said device is moved from its latched position and constructed and arranged to control the movement of one of 80 the pressing members for applying pressure to the work, and a lever manually operable for tripping said device and also setting the tools of the machine in operation.

In testimony whereof I have signed my 85 name to this specification in the presence of two subscribing witnesses.

LESTER L. GLIDDEN.
